UNITED STATES PATENT OFFICE.

JOSEPH J. BLACKMORE, OF JERSEY CITY, NEW JERSEY.

DESIGN FOR A RADIATOR.

SPECIFICATION forming part of Design No. 31,809, dated November 7, 1899.

Application filed October 4, 1899. Serial No. 732,582. Term of patent 14 years.

To all whom it may concern:

Be it known that I, JOSEPH J. BLACKMORE, a citizen of the United States, residing at 24 Brinkerhoff street, Jersey City, county of Hudson, State of New Jersey, have invented a certain new and useful Design for a Radiator, fully described and represented in the following specification and the accompanying drawings, forming a part of the same.

The design is illustrated in the annexed drawings, in which—

Figure 1 is an edge view of the radiator. Fig. 2 is a side elevation of the radiator, and Fig. 3 is a cross-section on line 3 3 in Fig. 2.

The radiator-body is of substantially rectangular form, with the usual feet at the lower corners and bosses *a* upon opposite sides near the top and bottom. Vertical slots *b* are extended entirely through the body of the radiator, forming a central column *c* and marginal columns which are of special shape, as shown in Fig. 3.

The distinguishing feature of the radiator is the cross-section of the marginal columns, (shown in Fig. 3,) which are each of wedge shape with the apex *d* of the wedge upon the

edge of the radiator and the sides of the wedge provided with three convex ridges *e*. The base of the wedge adjacent to the slot is of convex shape.

The top of the radiator, like the side columns, is of wedge shape, as shown in Fig. 1, with the apex of the wedge at the top and the convex ridges *e* extended horizontally.

The corners of all the columns are provided with small beads *f*; but these do not in practice form a prominent feature of the design, the essential feature of which is the triangular form of the marginal columns and their sides provided with the three convex ridges *e*.

Having thus set forth the nature of my design, what I claim, and desire to secure by Letters Patent, is—

The design for a radiator, substantially as herein shown and described.

In testimony whereof I have hereunto set my hand in the presence of two subscribing witnesses.

JOSEPH J. BLACKMORE.
